UNITED STATES PATENT OFFICE.

EMIL A. BEYL, OF MINNEAPOLIS, MINNESOTA.

SELF-ALIGNING TAKE-UP BOX AND ROLLER BEARING.

Application filed July 30, 1927. Serial No. 209,528.

My present invention has for its object to provide a simple and highly efficient self-aligning take-up box for elevator boots and the like and a roller bearing for take-up boxes, pillow blocks, rigid boxes and the like, and to this end, generally stated, consists of the novel devices and combinations of devices hereinafter described and defined in the claims.

10 In the accompanying drawings, which illustrate the invention, like characters indicate like parts throughout the several views.

Referring to the drawings:

Fig. 1 is a side elevation of a self-aligning take-up box and roller bearing embodied therein, with some parts broken away and sectioned;

15 Fig. 2 is a view principally in longitudinal central section taken on the line 2—2 of Fig. 1;

20 Fig. 3 is a view partly in plan and partly in horizontal section taken on the line 3—3 of Fig. 1;

25 Fig. 4 is a perspective view of the key for the take-up screw;

Fig. 5 is a perspective view of the ring removed from the housing;

30 Fig. 6 is a perspective view of the collar removed from the shaft and the housing;

35 Fig. 7 is a view partly in side elevation and partly in section showing the invention embodied in a pillow block; and

Fig. 8 is a view principally in section taken on the line 8—8 of Fig. 5.

40 Referring first to the invention as shown in Figs. 1 to 6, inclusive, the numeral 9 indicates a pair of upright spaced channel bars having their flanges turned toward each other to afford pairs of rails 10. The lower ends of the channel bars 9 are rigidly but detachably connected by a crosstie bar 11, and the upper ends thereof are rigidly but detachably connected by a head block 12. It

45 will be noted that the head block 12 is in the form of a channel set in a horizontal plane and having closed ends connected by a pair of nut-equipped bolts 13 to the webs of the channel bars 9 which permit turning movement of the head block 12 about a horizontal axis between the pairs of rails 10, for a purpose that will presently appear. To the webs of the channel bars 9 are rigidly secured angle bars 14 which afford mountings by which the take-up box may be secured to an elevator boot or other support.

50 Obviously, the channel bars 9, crosstie bar 11,

and head block 12 constitute a frame or a box, for a purpose that will presently appear.

55 Mounted between the pairs of rails 10 is an open faced housing 15 having a spherical periphery which engages the rails 10 and guides the housing 15 for raising and lowering movements and at the same time permits universal movements thereof. The 60 housing 15 is held suspended between the rails 10 by a long take-up screw 16, the lower end of which is removably swivelled at 17 in the top of the housing 15 and held by a key 18 against removal therefrom. The 65 key 18 is held against removal from its seat by the web of one of the channel bars 9.

70 The take-up screw 16 extends loosely through a pair of aligned holes in the flanges of the head block 12 and has applied thereto a nut 19 mounted in the channel of said head block which holds the same from turning, but with sufficient clearance to permit angular movement of the take-up screw 16 during the universal movements of the housing 15. Said take-up screw 16 has a square end 20 for the application of a wrench to turn said screw to raise or lower the housing 15.

75 Within the housing 15 is a roller bearing 80 of well known commercial make which comprises rollers 21 and inner and outer races 22 and 23, respectively. By reference to Fig. 2 it will be noted that the inner ends of the races 22 and 23 engage the back of the housing 15 and that the inner race 22 is considerably wider than the outer race 23 and projects outward thereof. A ring 24 is telescoped over the outer projecting end of the inner race 22 and its inner face engages the 85 outer end of the outer race 23. The length of the rollers 21 is such that they are free to turn between the back of the housing 15 and the ring 24.

90 Integrally formed with the ring 24 is an 100 outturned peripheral flange 25, and a face plate 26 is rigidly but detachably secured by a screw 27 to the housing 15. This face plate 26 is engaged by the flange 25 on the ring 24 and clamps said ring and the outer 105 race 23 together and between said face plate and the back of the housing 15, and holds the same from turning in respect to said housing. To further secure the outer race 23 from turning in the housing 15, the same 110 is secured thereto by a pin 28.

A shaft 29 is mounted in the inner race

22, extends through a shaft passage in the back of the housing 15, and has a collar 30 applied thereto which extends loosely through an axial aperture in the face plate 26. This collar 30 has an external flange 31 integrally formed with its inner end, which loosely fits between the ring 24 and face plate 26 and within the flange 25 to permit free rotation of said flange 31. A common key 32 is provided for securing the inner race 22 and the collar 30 to the shaft 29 for rotation therewith, as shown in Fig. 2.

10 A set screw 32' holds the key 32 against endwise movement in respect to the shaft 29 and in turn holds the collar 30 against axial movement on said shaft. Attached to the housing 15 is a nipple 33 through which oil may be introduced into the roller bearing. Formed in the ring 24 is a multiplicity of 20 circumferentially spaced holes 34 for the escape of a lubricant from the roller bearing to the flange 31 for lubricating the same.

Obviously, the collar 30 and its flange 31 hold the shaft 29 against end thrusts in either 25 direction. It is also evident that the housing 15 is self-aligning with the shaft 29 in the various different positions it might take.

To prevent the housing 15 from turning with the shaft 19 there is integrally formed 30 with said housing upper and lower pairs of fingers 35 which extend between the rails 10 of each pair and arranged to engage the webs of the channel bars 9. The width of the 35 fingers 35 is such as not to interfere with the endwise movement of the housing 15 between the rails 10.

By removing either the crosstie bar 11 or the head block 12, the housing 15 and the parts carried thereby may be lifted from the 40 frame. After the housing 15 has been moved into a position in which the key 18 extends either above or below the channel bars 9, said key may be removed to release the take-up 45 screws 16 from the housing 15.

Referring now to the invention as illustrated in Figs. 7 and 8, the elements 36 to 50, inclusive, are identical with corresponding elements 15, 21 to 34, inclusive. In this

structure, the housing 36 is mounted in a convex seat formed in a pillow block 51. Obviously, this mounting of the housing 36 permits universal movement thereof in said pillow block so that the same is self-aligning with the shaft 45.

What I claim is:

1. The combination with an open faced housing having a shaft passage in its back, of an anti-friction bearing in the housing including inner and outer races, a shaft mounted in the inner race and extending through said passage, a ring loosely surrounding the outer end portions of the inner race and bearing against the outer end of the outer race, said ring having an outturned peripheral flange, a face plate detachably secured to the housing and engaging the outer edge of the flange on the ring and clamping said ring and the outer race together and between the face plate and the back of the housing to hold the same from turning in the housing, and a collar on the shaft having an external flange extending loosely between the ring and face plate, said collar being held against axial movement on the shaft, said inner race being held for rotation with the shaft.

2. The combination with an open faced housing having a shaft passage in its back, of an anti-friction bearing in the housing including inner and outer races, a shaft mounted in the inner race and extending through said passage, a ring loosely surrounding the outer end portions of the inner race and bearing against the outer end of the outer race, a face plate detachably secured to the housing, a spacing flange between the ring and face plate, said spacing flange, ring and outer race being clamped between the face plate and the back of the housing to hold the same from turning in the housing, and a collar on the shaft having an external flange extending loosely between the ring and face plate, said collar being held against axial movement on the shaft, said inner race being held for rotation with the shaft.

In testimony whereof I affix my signature.
EMIL A. BEYL.
